United States Patent Office.

JOHN C. BREWSTER, OF NEW YORK, N. Y.

Letters Patent No. 99,143, dated January 25, 1870.

IMPROVEMENT IN DESULPHURIZING-OVENs.

The Schedule referred to in these Letters Patent and making part of the same.

I, JOHN C. BREWSTER, of the city, county, and State of New York, have invented certain new and useful Improvements in Desulphurizing-Ovens, of which the following is a specification.

Nature and Objects of the Invention.

My invention relates to furnaces or ovens for desulphurizing ores or minerals which have been previously stamped or crushed; and

My improvements consist in a novel combination and arrangement of parts for operating a revolving table, and removing the material from the furnace after it has been desulphurized.

Description of the Accompanying Drawings.

Figure 1 is a perspective view of my improved oven. Figure 2 is a vertical transverse section of the same. Figure 3 is a view of the air-tube F.

General Description.

A is the base of the oven, which is constructed, preferably, of a circular form, and is provided with the necessary furnace and chimney.

B is the top of the oven, constructed of an arched shape, to deflect the flames and heat upon the ore, and provided with a hopper, D, for introducing the ore.

The revolving table C rests upon the anti-friction rolls f f, which play in the grooves d e, the former situated in the base of the oven, and the latter in the under side of the table; and motion is imparted to it through the shaft a, the pinion b of which gears with the teeth in the under side of the table. The surface of the table is composed of a stratum of fire-clay,

which is laid within the flange or rim on the circumference.

The tube F, through which the air is admitted to the interior of the oven, is situated immediately above the surface of the table, and is provided with a series of apertures, i, and a series of fingers or wipers, j, so that, as the table revolves beneath it, the air is thrown down through the apertures of the tube upon the ore, while the latter is kept in motion and constantly stirred by the action of the wipers.

The supply of ore from the hopper D, regulated by the valve J in it, falls upon the centre of the revolving table, where it is spread by the joint action of the wipers and currents of air, and gradually worked off the edge of the table, and falls into the channel g. A series of sweeps, h h, attached to the under side of the table, then act upon it, to discharge it from the orifice G.

Claims.

I claim, as my invention—

1. The combination, with a furnace provided with a revolving table, of the mechanism for operating the revolving table, consisting of the grooved bed d, groove e, gear c, pinion b, and anti-friction-rolls f, substantially as described, and for the purposes specified.

2. The combination, with the revolving table, of the wipers h, for automatically removing the mineral from the furnace, substantially as described and specified.

JOHN C. BREWSTER.
